US0D1044882S

(12) **United States Design Patent** (10) **Patent No.:** **US D1,044,882 S**
(45) **Date of Patent:** **** Oct. 1, 2024**

(54) **WORK VEHICLE**

(71) Applicant: **Deere & Company**, Moline, IL (US)

(72) Inventor: **Brian L. Andersen**, Reinbeck, IA (US)

(73) Assignee: **DEERE & COMPANY**, Moline, IL (US)

(**) Term: **15 Years**

(21) Appl. No.: **29/865,172**

(22) Filed: **Jul. 12, 2022**

Related U.S. Application Data

(62) Division of application No. 29/684,678, filed on Mar. 22, 2019, now Pat. No. Des. 976,968.

(51) **LOC (14) Cl.** **12-09**

(52) **U.S. Cl.**

USPC **D15/23**

(58) **Field of Classification Search**

USPC D15/10-12, 22-26
CPC B62D 33/0617; B62D 49/00-085

See application file for complete search history.

(57) **CLAIM**

The ornamental design for a work vehicle, as shown and described.

DESCRIPTION

FIG. 1 is a perspective view of a work vehicle according to my new design;

FIG. 2 is a first side elevational view thereof;

FIG. 3 is a second side elevational view thereof;

FIG. 4 is a front end elevational view thereof;

FIG. 5 is a rear end elevational view thereof; and,

FIG. 6 is a top plan view thereof.

The broken lines shown in the drawings illustrate portions of the article and form no part of the claim design.

1 Claim, 6 Drawing Sheets
